J. S. LENNOX,
STATIONARY INDUCTION APPARATUS,
APPLICATION FILED DEC. 22, 1920.

1,436,968.

Patented Nov. 28, 1922.

Inventor:
John S. Lennox,
by Arthur G. Davis
His Attorney.

UNITED STATES PATENT OFFICE.

JOHN S. LENNOX, OF NORWICH, CONNECTICUT, ASSIGNOR TO GENERAL ELECTRIC COMPANY, A CORPORATION OF NEW YORK.

STATIONARY INDUCTION APPARATUS.

Application filed December 22, 1920. Serial No. 432,418.

To all whom it may concern:

Be it known that I, JOHN S. LENNOX, a subject of the King of Great Britain, residing at Norwich, in the county of New London, State of Connecticut, have invented 5 certain new and useful Improvements in Stationary Induction Apparatus, of which the following is a specification.

My invention relates to stationary induction apparatus and has for its object an improved arrangement of parts which is economical, mechanically strong and readily manufactured.

More particularly my invention relates to reactors which have a current limiting and protecting function and hence must not be materially damaged by overheating and must be mechanically rigid in order to withstand crushing stresses produced by short 20 circuits or other transients.

According to the present general practice, reactors designed for this purpose not infrequently have bare conductors carried in some manner by suitable radial supports. In order 25 to provide adequate ventilation over the turns it often occurs that there are considerable unsupported sections which may bend under the influence of the transient stresses with consequent disturbances in the subsequent 30 action of the reactor. This, of course, may be remedied by sufficiently multiplying the radial supports; but within a certain range of sizes it is objectionable to multiply the radial supports, as it adds materially to the 35 costs.

By my invention, however, an arrangement is provided in which the conductors support one another without the provision of special radial supports, the same to be 40 carried on a non-combustible plastic spool which is adapted to be standardized over a considerable range of sizes. In this manner a cheap and mechanically strong device is at the same time provided.

For a more complete understanding of the 45 nature and objects of my invention reference should be had to the following detailed description taken in connection with the accompanying drawing, in which:

Figure 1 is a view mainly in vertical section of a reactor constructed to embody my invention, while Fig. 2 is a top plan view 50 of the same reactor.

Referring now to the drawing and to Fig. 55 1 in particular, 10 denotes a plastic spool

preferably formed of non-combustible material, such as cement; and comprising a cylindrical body portion 11, which may be hollow as indicated, and disc shaped upper and lower end members 12 and 13 respectively. The lower end member 13 is shown as surmounting a plurality of insulating supports 14.

The cylindrical body portion 11 is shown as provided with a plurality of threaded 65 rods 15 anchored in its ends and which are adapted to pass through corresponding openings formed in the end members 12 and 13. These rods 15 have nuts and washers 70 engaging with their protruding ends in order to secure the end members in place on the body portion 11.

About the cylindrical body portion 11 and spaced concentrically therefrom are a plurality of nested insulating cylinders 20 75 which are adapted to support the windings 21 of the reactor. Each cylinder is shown as having a single layer of conductors wound helically thereon in abutting relation, the cylinders themselves being retained in the 80 desired concentric relation by the aid of vertical spacers 23, which are laid on the windings parallel to the geometrical elements of the cylinder and are preferably of sufficient thickness to fit snugly between the winding 85 and the next external cylinder. The innermost cylinder 20' is also spaced from the body portion 11 by means of vertical spacers, as shown.

By this construction, it is seen that the 90 cylinders 20 may be wound with any desired size or kind of winding independently and are then ready for assembly on the body portion 11 of the reactor, the cylinders being put in place before at least one of the end 95 members is finally secured in place. The cylinders are themselves preferably formed of non-combustible insulating material; while the windings thereon have a non-combustible insulating covering such as asbestos, and may be connected in any desired manner, here assumed to be in series.

In order to provide ventilation for a reactor constructed in this manner, the end members are provided with perforations 30 105 disposed near their peripheries as shown. In order further to distribute in an approximately uniform manner the incoming air entering a perforation in the lower member to the ducts between the cylinders 20, the 110

members 12 and 13 are provided with radial recesses 31 on their inner faces about the openings 30, as shown. These recesses permit the incoming volume of air to distribute 5 itself into parallel streams traversing substantially all the ducts between the cylinders 20 in the neighborhood of an opening 30. The superposition of the openings 30 in the upper member 12 over those in the lower member 13 tends to produce a "chimney 10 effect" inducing a rapid circulation of the air (or whatever the surrounding insulation medium may be) over the windings of the reactor.

15 The terminals of the assembled winding may be brought out through selected ones of the openings 30 as indicated in Fig. 2 at 34 and 35.

20 In order to provide the reactor, assembled as above described, with a suitable lifting means, I provide a centrally disposed rod or bolt 40 which passes through openings 41 and 42 in the upper and lower members 12 and 13 respectively and retain the same in 25 place by a nut and washer 43 at its lower end and a suitable eye-nut 45 at its upper end. This construction serves to assist in holding the parts together and by means of the eye at 45 provides a lifting means which 30 does not strain the original securing devices during a lifting operation.

The construction above described is substantially fire-proof and is well adapted to withstand the crushing stresses occasioned 35 by short circuits and like transients; since

such stresses can only tend to pinch the conductors on the cylinders 20 closer together without any consequent effects on the operation of the reactor. Moreover the cylinders 20 and body portion 11 may be made in 40 any desired lengths to produce reactors of different ratings over a given range for given standardized end members.

Having now described an embodiment of my invention which is at present the best 45 means known to me for carrying the same into effect, I would have it understood that this is merely illustrative and that I do not mean to be limited thereby to the precise details shown, nor restricted in the choice of 50 recognized equivalents except as defined in my claims hereunto annexed.

What I claim as new and desire to secure by Letters Patent of the United States, is:—

A reactor comprising a plastic non-combustible insulating spool composed of a body portion and separable end members, means for independently securing said end members to the body portion, spaced concentric insulating cylinders surrounding said body 55 portion, and windings on each of said cylinders, said end members having openings near their peripheries and in line with the spaces between said insulating cylinders to admit a cooling and ventilating medium 60 through said spaces.

In witness whereof, I have hereunto set my hand this 18th day of December, 1920.

JOHN S. LENNOX.
